MATERIAL HANDLING APPARATUS

Application filed July 25, 1929. Serial No. 380,937.

This invention relates to material transfer, and is more particularly concerned with means for conveying and transferring loose material from one depository such as a freight car, barge, etc., to another, which may be a similar transporting medium or a truck, for example.

An object of the invention is the provision of a mobile unit having material gathering and conveying means depending therefrom and distributing and reloading means to which the gathered material is conveyed, with provision for adapting the material gathering means to differentials in area and locations of the material in the particular depository.

Another object is the provision of means for progressively moving the gathering means along the material area at selected speeds best conforming to the removal rate and bulk of material.

A further object is the provision of a support for the mobile unit providing for bodily adjustment of the support and unit in a vertical direction. This in combination with provision for independent vertical adjustment of the material gathering means will permit the apparatus to be adapted to a wide range of variations in the elevations of discharging and receiving depositories for the material being handled.

These and other objects and features including provision for feeding material from opposite sides toward an intermediate material gathering point, and for adapting the feeding means to varying widths of depositories will be more clearly apparent from the following detailed specification which is to be read in conjunction with the accompanying drawings forming part thereof and in which—

Figure 1 is a view in side elevation of the material handling apparatus of the present invention as adapted for operation from above with reference removal and distribution by conveyance of material in a freight car therebeneath.

Figure 2 is a view in vertical section on the line 2—2 of the apparatus shown in Figure 1.

Figure 3 is a top plan view of the apparatus, and

Figure 4 is a longitudinal sectional detail of the lateral feeding means for moving the material to the area of operation of the 55 elevating conveyer.

As previously stated the apparatus is supported above the material to be handled. This material may, for example, be carried in a barge or other type of open top depository and the elevated support of the apparatus will extend above the barge. For the purposes of illustration, I have shown the material as deposited in an open top freight car and the material handling apparatus as mounted upon a trackway elevated above the car. In the drawings, Figures 1 and 2, 1 designates the rail bed upon which the freight car 2 rests. At the opposite sides of the rail bed and spaced from the rail thereof sufficiently to provide clearance are mounted hydraulic jack cylinders 3 which may, as shown, be supported upon concrete bases 4. These cylinders will be positioned in substantial vertical alinement 65 with the four corners of a rectangular elevated trackway indicated at 5 and formed of metal stringers 6 extending longitudinally of and parallel with the rails or rail bed 1 and mounting rails 6a upon their upper 70 faces. These stringers are rigidly interconnected by the end cross members 7 and have secured to and depending from their opposite ends the vertical supporting standards 8 reinforced at their point of connection thereto by gusset plates 9 and braced to the stringers by the diagonal tie plates 10 and connecting gussets 11. The standards 8 are of uniform length and may, as shown, be in the form of steel angles. Their 75 lower ends are fixed to plates 12 upstanding from a suitably reinforced metal base 13 which in turn is fixed to the upper end of the plunger 14 of the hydraulic jack cylinder 3. Since these cylinders may be of 80 any standard construction, suitable for this purpose, the details of their operating connections are omitted.

An elevated trackway such as described is of course intended to extend over the 100

5 barge or freight car whose contents are to be elevated and distributed. The length of the trackway will therefore be sufficient to cover the longitudinal storage area of the transport in which the material to be handled is deposited or carried and its stringers 6 are, as shown, in vertical planes beyond the outer edges of the rail bed 1.

10 Mounted on the elevated trackway is a mobile material elevating and distributing unit presenting a wheeled frame open between its sides above the car or transport 2 and mounting and having depending through the opening in the wheeled frame 15 and through the opening between the stringers 6, a material elevating conveyer whose lower end is designed to contact any material to be elevated, material receiving and distributing means being provided at 20 the upper end of this conveyer.

25 The frame chassis as best shown in Figures 2 and 3 is of channel formation and comprises the stringer channels 15 joined at their ends to the transverse channel frame members 16 which extend transversely of the trackway to terminate adjacent the rail 6a and which as shown in Figure 2 are provided with depending hangers 17, in which are journaled axles 18 mounting on their 30 ends the wheels 19 resting upon the track 6a and giving the unit mobility. One axle is provided with a sprocket wheel 20, Figures 1 and 2, through which the wheeled frame is moved longitudinally of the trackway. At one side of the stringers and extending laterally outward therefrom, an operator's platform 21 is secured and adjacent the platform and between the stringers extends a connecting bed plate 22 (Figure 3) 35 upon which the motor 23 is mounted. Adjacent the opposite ends of the stringers, triangular frames upstand from the stringers 15 in transverse alinement, these frames being, as shown, formed of angle irons 25 inclined upwardly toward each other, riveted at their lower ends to the stringers 15 and braced and connected at their upper ends by gussets 24. Brackets 27 are secured to the top of these frames and provided with 40 inwardly extending bifurcations 28 between which are mounted guide rolls 29. At the opposite end of the stringers 15 from the angle irons 25, vertical angle bars 30 upstand to a point in alinement with the upper 45 ends of the angle irons 25, and are connected thereto by longitudinally extending angle bars 31, shown in Figure 1. Mounted on the upper face of the angles 31 in transverse alinement are bearing brackets 32 in 50 which the ends of a counter-shaft 33 are journaled, this shaft, as shown in Figure 1, being positioned between the angle irons 25, and the motor 23. A narrow channel plate 34 cross connects the bearing brackets 32 55 and underlies the counter-shaft 33 to fur-

nish support for the intermediate bearings 35, 36 (Figure 2). The shaft 38 of the motor 23 extends outwardly beyond the line of the channels 15 to a point above the sprocket gear 20 of the axle shaft 18 at which point it is provided with a sprocket gear 39 connected by a sprocket chain 40 with the axle sprocket 20. Inwardly of the sprocket gear 39 a second sprocket gear 41 is mounted upon the motor shaft 38 and is connected by a sprocket chain 42 or other wrapping connector with a driving sprocket 43 (Figures 1 and 2) mounted on the counter-shaft 33 adjacent its bearing 36. This driving connection serves to transmit power from the motor shaft 38 through a friction clutch 44 to a hoisting drum 45, loosely mounted on the shaft and held against movement in cable lowering direction by suitable pawl and ratchet mechanism, the purpose of which as will be later seen is to maintain the conveyer and its housing in the position to which it is elevated through the drum and clutch. 70

75 The end of the motor shaft 38 opposite to the sprocket gear 39 similarly projects outwardly beyond the channel stringers 15 and is provided with a second sprocket gear 46 thereon. The corresponding end of the counter shaft 33 similarly projects and 80 mounts an alined sprocket gear 47 connected with the motor sprocket 46 through chain 48. Adjacent the sprocket gear 47 a friction clutch 49 connects the driven counter-shaft with a sprocket gear 50 from which a sprocket chain 51 extends upwardly to the driving sprocket gear 52 of a material elevating conveyer. 90

95 This conveyer is enclosed in a tubular housing 53 between the sides of which, at its open upper end, a driving shaft 54 extends and in which sides it is journaled, this shaft extending outwardly beyond one face of the housing and mounting the sprocket gear 52 thereon. The housing is provided on its opposite outer faces in line with the guide rollers 29, with a vertically extending trackway 55 in which the rollers extend to guide the conveyer housing for bodily vertical movement, the housing being supported by a cable 56 suitably attached as at 57 adjacent its lower end and extending to and winding on the hoisting drum 45 on the counter-shaft 33. At the lower end of the housing 53, bracket plates 58 depend from its sides and are vertically slotted and mount thereon vertically adjustable bearings 59 of standard construction to receive the lower shaft 60 of the conveyer. This shaft mounts a pair of spaced sprocket gears 61 (shown in dotted lines in Figure 2) over which run the chains 62 upon which are mounted the buckets 63 of an endless conveyer. The upper ends of the chains 62 carrying the buckets run over and are positively driven 100

130

by spaced sprocket wheels 64 mounted on the upper conveyer shaft 54. Preferably means are provided to permit slippage in the conveyer drive in the event of over load. As shown in Figure 1, an adjustable spring tensioned clutch indicated at 65 is interposed between the conveyer shaft 54 and the driving sprocket 52 yielding under predetermined excess load. At one side of the lower end of the conveyer housing 53 and extending in parallel with the conveyer sprocket shaft 60 is a depending scoop plate 66 designed to hold material to be impacted by the descending buckets 63 as the wheeled frame and its depending conveyer are moved longitudinally of the trackway, scooping a lane in the material and continuously elevating it as the unit moves on its trackway. The adjustable bearing 59 at the lower end of the conveyer is, obviously, for the purpose of taking up slack in the chain. Obviously, the lower end of the conveyer is initially adjusted to the height of the top level of the material to be excavated and is thereafter progressively lowered as the successive strata of the material is elevated.

In order that the wheeled carriage mounting the conveyer may be moved at speeds consistent with the rate of removal of the material and that the direction of movement of the conveyer may be reversed, a suitable changeable speed and reverse transmission designated generically at 67, Figure 2, is interposed on the motor shaft 38 between the driving sprocket for the frame wheel and the motor. This locates the transmission adjacent to the operator's platform 21. The transmission may conveniently be of the planetary type, pedal operated as in the case of the familiar planetary transmission of the Ford automobile, leaving the operator's hand free for the operation of the levers 68 and 69 operating, respectively, the clutch 46 for the hoist 45 and the clutch 49 for the conveyer drive, these clutch connections being only generically shown, since any suitable standardized form of clutch control may be used.

It will be obvious that the drive chain 51 for the upper shaft of the conveyer extends from a fixed sprocket 50 on the counter-shaft 33 to a sprocket 52 which is bodily movable vertically with the conveyer housing and that the drive chain 51 must be of a length to be taut in the maximum elevated position of the conveyer shaft and housing. Consequently when the housing is lowered, slack will occur in the chain. Provision for maintaining the chain under tension in compensation for this slack is provided in the form of an arm 70 (Figure 1) having a hub 71 at its lower end journaled on a pin 72 outstanding from the face of the conveyer housing 53, and having on its upper end, an offset at 73 mounting a roll 74 overlying and

engaging the inner face of the driving chain 51. When the conveyer and its housing are lowered, the arm 70 will swing outwardly to the left and by its weight maintain the chain 51 under driving tension.

Provision for transferring the material elevated in the buckets 63 is made in the form of a downwardly inclined chute 75 which may form an integral or rigid extension from the open upper end of the conveyer housing 53, this chute being joined at its lower end with reversely inclined distributing chutes 76, 77 extending laterally of the wheeled frame and downwardly to points beyond the edges of the trackway. A hinged gate 78 (Figure 1) at the junction of the upper ends of the reversely inclined chute 75 selectively places this chute in communication in either distributing chute 76, 77 and therefore may distribute the material elevated by the bucket conveyer to transports such as trucks or other freight cars positioned at either side of the car 2 or other material holder which is being unloaded.

In order to adapt the conveyer to the width area of the material to be elevated, as for example, the width of the freight car 2, means have been provided for gathering the material inwardly toward the conveyer buckets upon opposite sides of the conveyer and from the outer edges of this area, the means provided being in the form of gathering units driven from the lower conveyer shaft and variable in number to include the full width of the storage area. These gathering units have in effect a screw action and are best seen in Figures 1, 2 and in detail in Figure 4.

Referring to Figures 2 and 4, it will be seen that the lower conveyer shaft 60 extends outwardly and lies within the bearing brackets 58 and is threaded. On the opposite ends of this shaft and threading successively onto each other are a series of bladed material gathering sleeves 85 having radially projecting blades 86 thereon in-turned toward the conveyer, the successive bladed sleeves being quartered when arranged in a series of four as shown in Figure 1 so that they form in effect an interrupted screw effective to gather material from the lateral outer extremities of the storage area of the freight car or barge inwardly toward the center where the conveyer buckets scoop it up and elevate it for discharge downwardly in the chute 75. Each of these bladed sleeves are formed with interfitting threaded sockets 87 and stems 78 providing male and female joints, the threads being such that the direct back pressure of material against the buckets in loading will tighten the bladed sleeves upon each other and upon the shaft 60 rather than loosen them. The bladed sleeves will be ap-

plied with their threaded sockets innermost and the threaded stem at the outer end of the outermost bladed sleeve will be protected by an end nut 79 having a threaded socket therein fitting over the projecting threaded sleeve 78 of this end unit and protecting it from injury through contact with the material being gathered inwardly.

It will be obvious that the number of 10 the units employed will be determined by the transverse area of the car or other depository 2 within which the material is housed so that by the provision of these bladed sleeves, the conveyer is made adaptable to variance in the transverse dimension of the storage area.

It will be obvious that in the operation of elevating the material, the lower end of the conveyer will be initially positioned to 20 engage the top strata or top layer of material to be elevated and will be moved with the wheeled frame from one end of the car to the other with the conveyer operating to elevate the material; will then be reversed 25 and lowered to take the next strata below and the same operation again performed until the contents of the car have been removed. The hoisting drum 45 will, as previously described be provided with suitable 30 means such as a pawl and ratchet mechanism for holding the drum and the conveyer at the desired point until further downward adjustment is desired. The power hoist through its friction clutch is 35 operative to elevate the conveyer and by slippage it is permitted to lower to the desired point at which it is held by the pawl and ratchet mechanism. The conveyer drive from the motor shaft being operated 40 independently from the drive to the wheel shaft of the conveyer truck, or wheeled frame, permits independent operation of the wheeled frame and its conveyer housing for bodily movement lengthwise on the 45 trackway in both directions without interference with the operation of the conveyer.

While the described construction represents a preferable embodiment of the invention, it will be obvious that it is subject 50 to variation and change to meet requirements of manufacture and adaptation to different uses in consonance with the spirit of the invention and the scope of the appended claims.

55 What I claim, therefore, and desire to secure by Letters Patent is:

1. In material handling apparatus, an elevated supporting frame, an endless conveyer depending from said frame to contact material to be elevated with its lower end and mounting a rotating conveyer operating shaft at its lower end, and a plurality of axially aligned material gathering and feeding units secured to the opposite ends of 65 said conveyer shaft and extending axially

outward from the ends of said shaft, said units comprising hubs having interthreading male and female joints, and having material engaging wings extending outwardly therefrom and formed to feed the material engaged laterally inward to said conveyer the threads of said hub joints being inclined to tighten by the thrust of material against said wings.

2. In material handling apparatus, a frame, an endless conveyer depending from the frame to contact material to be elevated with its lower end and mounting a rotating conveyer operating shaft at its lower end, and a plurality of axially aligned material gathering and feeding units secured to an end of the conveyer shaft and extending axially outward from the end of the shaft, the units comprising hubs having interthreading male and female joints and having material engaging wings extending outwardly therefrom and formed to feed the material engaged laterally inward to the conveyer, the threads of the hub joints being inclined to tighten by the thrust of material against said wings.
